U-SHAPED KEEPER LOCK FOR SEMI TRAILERS AND THE LIKE

John R. Gerlach, Monterey Park, Calif., assignor to Emhart Corporation, Bloomfield, Conn.

Filed Mar. 19, 1973, Ser. No. 342,732

Term of patent 14 years

Int. Cl. D8—07

U.S. Cl. D8—114

FIG. 1 is a side elevational view of my U-shaped keeper lock for semi trailers and the like showing my new design;

FIG. 2 is a right end view thereof;

FIG. 3 is a left end view thereof;

FIG. 4 is a top plan view thereof; and

FIG. 5 is a bottom plan view thereof.

I claim:

The ornamental design for a U-shaped keeper lock for semi trailers and the like, as shown.
